COMBINED RADIO, PHONOGRAPH, AND TELEVISION CABINET

Richard Prince, Elmhurst, N. Y.

Application October 19, 1948, Serial No. 149,186

Term of patent 7 years

(Cl. D56—4)

To all whom it may concern:

Be it known that I, Richard Prince, a citizen of the United States, residing at Elmhurst, New York, in the county of Queens and State of New York, have invented a new, original and ornamental Design for a Combined Radio, Phonograph and Television Cabinet, of which the following is a specification, reference being had to the accompanying drawing, forming a part thereof:

In the drawing:

Fig. 1 is a front elevational view of a combined radio, phonograph and television cabinet, showing my new design.

Fig. 2 is a side elevational view of the same;

Fig. 3 is a perspective view of the same with the doors in open position; and

Fig. 4 is a vertical sectional view taken on the line 4—4 of Fig. 1.

I claim:

The ornamental design for a combined radio, phonograph, and television cabinet, as shown.

RICHARD PRINCE.
